UNITED STATES PATENT OFFICE.

AUGUSTUS C. SAXTON, OF CHICAGO, ILLINOIS, ASSIGNOR TO H-R MANUFACTURING COMPANY, OF CHICAGO, ILLINOIS, A CORPORATION OF ILLINOIS.

LOCK.

Application filed May 27, 1922. Serial No. 564,052.

To all whom it may concern:

Be it known that I, AUGUSTUS C. SAXTON, a citizen of the United States, residing at Chicago, Illinois, have invented certain new and useful Improvements in Locks, of which the following is a specification.

My invention relates to that type of locks designed to prevent operation of the gear shift lever of a motor vehicle and among the objects thereof are to provide an improved structure of the character stated; to provide a structure which will positively lock the control lever in neutral position; to provide a structure which cannot, by any of the means ordinarily employed for that purpose, be rendered ineffective for the intended use; and such further objects, advantages, and capabilities as will later more fully appear.

My invention further resides in the combination, construction, and arrangement of parts illustrated in the accompanying drawings and, while I have shown therein a preferred embodiment of my invention, I desire the same to be understood as illustrative only and not as limiting said invention.

In the drawings annexed hereto and forming a part hereof,

Fig. 1 is a broken plan view of my new construction, the control lever being shown in section.

Fig. 2 is a longitudinal section substantially along the plane indicated by the line 2—2 Fig. 1.

Fig. 3 is a broken sectional elevation, approximately at a right angle to the plane of Fig. 2.

Fig. 4 is an expanded perspective view of the internal portions of my new lock.

Fig. 5 is an elevation of the inner face of the lock cylinder and a part associated therewith.

Fig. 6 is a fragmentary sectional elevation somewhat similar to Fig. 3 but with the parts in a different position.

Referring more in detail to these drawings numeral 1 designates the transmission housing, 2 the lever and 3 the lock for securing the lever in neutral position. Within the body 4 of the lock casing are the parts for sustaining and maintaining the control lever in position and permitting the same to oscillate to any one of the several controlled positions. The lever ball seat 5 is held in adjusted position with relation to

the body member 4 by means of a screw 6 which is ordinarily screwed in tightly and then finished off flush with the exterior surface of the lock. A ring 7 normally tends to hold the control lever from rotation about its axis and is itself locked against a shoulder on the interior of the body member by means of a screwthreaded ring 8 provided at its bottom with a flange 9 upon which rests a coil spring 10. The purpose of this coil spring is to force the annular block 11 up against the lever ball 12, as will be obvious. The ring 8 having been turned in until it tightly holds ring 7 in position is locked in place by means of a bolt or bolts 13 which pass through the body member 4 and into the ring 8 and are then finished off flush with the surface of the body member. A screw or screws 14 serve to hold the body member 4 in proper position on the housing 1 and these screws are likewise finished off flush with the surface of the lock. It will be seen from the above that when the parts have all been placed in position and the screws cut or broken off until their outer ends are just flush with the lock body, it will be practically impossible to remove the lock unless provided with the proper equipment. It will also be necessary to have the lock free from the machine and where it can be secured within proper machinery for operation.

The lock body 4 is provided with an upwardly extending flange 15 having at its upper end an inwardly directed flange 16, parts 15 and 16 having their upper surface convex, the center of curvature being located at the center of curvature of the ball 12. A curved plate 17 whose inner surface has the same radius of curvature as the upper surface of parts 15 and 16, surrounds the control lever 2 and moves therewith, sliding over the curved upper face of said members. Outside of flange 15 is a locking ring 18 which may be raised up into the path of plate 17 to prevent the same from lateral motion in any direction. Encasing these members is a sleeve which is fastened to the body member 4 by means of screwthreading and then permanently locked in position by means of screw 6 referred to above, after the parts have been properly positioned.

The details of the locking mechanism are shown most clearly in Fig. 4 from which it

will be seen that a cam-plate 19 provided with a plurality of cams 20, preferably not less than 5 in number, cooperates with locking ring 18 to raise the same into locking position as shown in Fig. 6. As indicated above, these parts are enclosed in a casing 21 within which cam-plate 19 is rotatively adjusted until cams 20 accurately fit in the cam notches 22 in locking ring 18 when this ring is in unlocked position. When the above noted adjusted position is attained, locking ring 23 is turned in to lock the cam-plate 19 firmly in adjusted position.

The locking ring 18 is provided in its periphery with a substantially cylindrical perforation 24 in which slides a cylindrical pin 25. Pin 25 has a perforation 26 extending therethrough for the reception of a pin extending from the face of block 28 pivoted on the inner end of the lock cylinder. This block 28 is secured to the end of the lock cylinder 30 by means of a cam plate 29 having on one edge a cam 31 of appropriate size and shape. In the present example this is shown as extending one fourth of the way around the plate 29 and block 28 also extends around one fourth of the plate 29. It will therefore be seen that during the first half revolution of the key and cylinder 30 cam 31 does not engage with either shoulder 32 or shoulder 33 of the block 28, but during the second half revolution this block will be caused to turn about the cylinder 180°. As will be obvious this movement will cause locking ring 18 to turn about its axis, thus causing its cam faces to rise up on the cam faces of the cams 20. When this happens ring 18 rises so that its upper end comes in contact with the edge of plate 17 thus preventing the same from being moved laterally. This plate 17 is held down in contact with flange 16 by means of a flange 34 at the upper edge of casing 21.

It will be seen from the above description that when the parts are all adjusted into desired relation and secured in adjusted positions, it will be next to impossible to get them out of such adjusted positions without completely destroying the lock, the parts being made of very hard material so that they are not susceptible to attacks with cold chisel, sledge, hack-saw and other similar tools.

It is of course understood that the specific description of structure set forth above may be departed from without departing from the spirit of my invention as set forth in this specification and the appended claims.

Having now described my invention,
I claim:

1. In a lock of the character described, means for supporting a motor vehicle control lever and permitting same to be moved to various operative positions; means surrounding the control lever and moving

therewith as the lever moves to its operative positions; and means movable into the path of movement of the second named means to prevent its movement and thereby prevent movement of the control lever, and key operated means for moving the third means.

2. In a lock of the character described, a body member carrying a control lever, said body member being hollowed out to permit the lever to be oscillated into various operative positions; a member surrounding the lever and having its edge enclosed within the body member, said member surrounding the lever being movable within the body member; and means movable into the path of movement of the lever surrounding member to prevent movement thereof.

3. In a lock to be mounted upon a transmission casing; a body member; said body member having in its upper part an aperture; means therein for supporting a control lever; means surrounding the control lever and extending laterally into the opening in the body member; and means in the aperture in the body member movable into a position for preventing movement of the member surrounding the control lever.

4. In a lock of the character described a lock body adapted to be secured to the upper portion of a transmission casing and to have a control lever pivotally supported therein; said lock body having in its upper portion an internal peripherally disposed aperture for the reception of locking means; said body also having an inwardly extending groove for the reception of a movable plate; a plate surrounding the control lever and movable into various positions in the inwardly extending groove, as said lever moves to its various operative positions; and locking means in the peripherally disposed aperture adapted to be moved into position to prevent motion of the plate surrounding the control lever.

5. In a lock of the character described, a body member provided with an upwardly and inwardly extending flange; a lock cylinder carrying sleeve secured to said body member and spaced from said flange; a plate adapted to surround a control lever and extend into the space between the flange and lock carrying sleeve; and means actuated by the cylinder into the path of movement of the plate, whereby said plate is prevented from movement within the space into which it extends.

6. In a lock of the character described, a body member having a flange located around the inner periphery thereof; a lock cylinder carrying sleeve secured to the body member; a cam plate fixedly secured between the flange and sleeve; and a locking ring having cams corresponding to the cams on the cam plate and interfitting

therewith; and means for rotating said locking ring to cause the cooperating cams to move the locking ring axially.

7. In a lock of the character described, 5 a locking ring having cams formed thereon and having in its periphery a longitudinally extending aperture; a pin movable in said aperture; a lock cylinder having a block pivoted thereon, and provided with 10 means for actuating said block; said block carrying means for actuating said pin to actuate the locking ring.

8. In a lock of the character described, 15 a lock body having an internally arranged axially extending flange; a lock cylinder carrying sleeve secured to said lock body and spaced from said flange; a cam plate adjustably secured within the space between the flange and sleeve; a locking ring provided with cams cooperating with the cams 20 on the said plate; and means connecting the lock cylinder and the locking ring so that rotation of the cylinder will cause rotation and axial movement of the locking 25 ring.

9. In a lock of the character described, means for supporting a motor vehicle control lever and permitting same to be moved to various operative positions; means connected to the control lever and moving therewith as the lever moves to its operative positions; and means movable into the path of movement of the second named 30 means to prevent its movement and thereby prevent movement of the control lever, and a movable lock member for moving the third named means.

10. In lock mechanisms for shift levers for transmission devices comprising a support 35 and a lever operatively supported thereby, a member movable with the lever,

a second member movable into and out of the path of movement of said first mentioned member, a lock element connected to said second mentioned member and movable to move the same to or out of the path of movement of said first mentioned member.

11. In a device of the class disclosed, a support, a shift lever operatively supported thereby, a lock member connected to the lever and movable in the support, a second lock member movable in the support into and out of the path of movement of the first mentioned lock member, a third lock member connected to the second lock member and operable to move said second lock member into and out of the path of movement of the first lock member.

12. In a device of the character disclosed, 60 a support, a shift lever operatively supported thereby, a lock member connected to the lever and movable in the support, a second lock member movable in the support into and out of the path of movement of the first mentioned lock member, a third lock member connected to the second lock member and operable to move said second lock member into and out of the path of movement of the first lock member, and means for supporting the second lock member in the path of movement of the first lock member whereby the third lock member is free and receives no re-action from the second lock member.

In witness whereof, I hereunto subscribe my name to this specification in the presence of two witnesses.

AUGUSTUS C. SAXTON.
